UNITED STATES PATENT OFFICE.

JAMES R. CLARK, OF CICERO, ILLINOIS.

DESIGN FOR A TOY BOAT.

Application filed September 16, 1922. Serial No. 3,739. Term of patent 7 years.

To all whom it may concern:

Be it known that I, JAMES R. CLARK, a citizen of the United States, residing at Cicero, in the county of Cook and State of Illinois, have invented a new, original, and ornamental Design for Toy Boats, of which the following is a specification, reference being had to the accompanying drawing, forming part thereof.

The figure is a perspective view of a toy boat, showing my new design.

I claim:

The ornamental design for a toy boat, as shown.

JAMES R. CLARK.
